UNITED STATES PATENT OFFICE.

FRANCIS M. TYLER AND WILLIAM W. TYLER, OF AUBURNDALE,
MASSACHUSETTS.

SWITCH-OPERATING MECHANISM FOR STREET-RAILWAYS.

SPECIFICATION forming part of Letters Patent No. 606,438, dated June 28, 1898.

Application filed December 22, 1897. Serial No. 662,967. (No model.)

To all whom it may concern:

Be it known that we, FRANCIS M. TYLER and WILLIAM W. TYLER, of Auburndale, county of Middlesex, and State of Massachusetts, have invented an Improvement in Switch-Operating Mechanism for Street-Railways, of which the following description, in connection with the accompanying drawings, is a specification, like letters on the drawings representing like parts.

Our invention is an improvement in street-railway-switch-operating devices, and has for its object the provision of simple means for enabling the driver or motorman of a street-car to reverse at will any switch just before his car reaches it.

Many devices have been proposed for accomplishing the general object above mentioned; but, so far as we are aware, such devices have been invariably complex or else entirely impracticable for the requirements of actual service. Accordingly we have devised the mechanism as more particularly set forth hereinafter, by means of which extreme simplicity, strength, durability, and effectiveness are attained, together with certainty of operation, minimum cost of production and maintenance, ease of operation, and adaptability to usual switch-points and railway connections.

In general our invention comprises a rotary drum and beveled spur-wheel at one side of one of the rails forming the track, preferably at the inner side of the right-hand rail approaching the switch, in connection with a rock-shaft provided with divergent arms, one of which engages a cam-groove in said drum and the other of which is connected with the switch-point, our invention also preferably including electric devices for preventing the clogging or stoppage of parts by snow and ice, and other details for keeping out water, mud, and moisture.

By our invention the switch can be positively thrown in either direction at will by a special device on the approaching car, and the latter will be automatically restored to its normal position immediately upon having thrown the switch.

The details of construction of our invention and various other advantages thereof will be

pointed out in the course of the following description, reference being had to the accompanying drawings.

In the drawings which illustrate a preferred embodiment of our invention, Figure 1 is a top plan view thereof, parts being broken away. Fig. 2 is a side elevation thereof, parts being shown in longitudinal vertical section. Fig. 3 is a longitudinal vertical section taken on the line 3 3, Fig. 1. Fig. 4 is an enlarged broken detail in section taken on the dotted line 4 4, Fig. 1. Fig. 5 is a transverse section taken on the line 5 5, Fig. 1. Fig. 6 is an enlarged transverse section taken on the line 6 6, Fig. 1.

The main rail A, siding-rail A', and switch-point A², pivoted at a, may be and are of usual construction, being herein shown as embedded in usual street-paving blocks B. At one side, preferably the inner side of the rail A, we provide a channeled block C, herein shown as formed integral with the rail and as having a flaring lip c at its forward end away from the switch-point, and adjacent its other end is provided with an incline c', said channeled block being preferably deflected, as shown at c², at its end nearer the switch.

In a suitable housing adjacent the block C we have mounted a drum D, having a peripheral cam-groove d, herein shown as serpentine in its course and as provided with alternate high and low dwells or straight portions d¹, d² for a purpose presently to be described. At its upper end the drum D is provided with a plurality of arms or spurs d³, said spurs being herein shown as carried by a wheel d⁴, although they may, if desired, be formed integral with the drum itself. Each spur has a radial face or edge d⁵ and a beveled edge d⁶, as is clearly shown in Fig. 1, these arms being of sufficient length to project through a slot c³ in the outer rib or wall of the channel-block C and extend across the channel thereof to be struck by a tappet on the car, as will be presently explained.

The object of the bevel d⁶, taken in connection with the particular location of the parts as described, is to provide automatic means for removing dirt, stones, slush, or other debris from the channel and in front of the ratchet-wheel or drum-arms. As the latter

are revolved they slide against any obstruction which may have lodged in their path and remove it with a forcible wedging action, not only thereby automatically clearing their own path, but shoving the obstruction away from the drum. This feature of our invention is of much importance from a practical standpoint.

The housing and drum are of special construction, with a view absolutely to preclude all possibility of the clogging of the moving parts by the entrance of snow, water, &c.

Referring to Figs. 3 and 6, it will be seen that we have provided a special housing, shown as comprising opposite castings E E', bolted together at e and having internal annular ribs e' projecting upwardly from the bottom thereof to coöperate with the downwardly-projecting flanges or eaves d' on the drum for shedding water, and inwardly-extending top flanges e², having annular ribs e³ on their upper surfaces to enter corresponding grooves d⁸ in the wheel d⁴, a flanged cover-plate e⁴ being bolted at e⁵ to the housing and completing the inclosure for the drum. By this construction it will be evident that no dirt and slush can work into the mechanism, for the reason that its entrance is prevented in the first place by the joint of the cover with the housing and in the next place by the interlocked rib and groove e³ d⁸, and if any moisture should work beyond that point it would be deflected by the eaves d' of the drum and fall outside of the flange e', whence it would find an outlet through the opening e⁶, Fig. 6.

In order to prevent the possibility of any moisture freezing between the moving parts, so as to clog and render them inoperative, we have provided an electric heater e⁷, held by brackets e⁸ beneath the flange e², so as to maintain more or less warmth in the adjacent parts by the passage of an electric current through the coil of the heater.

In the cam-groove d of the drum an arm f of a rock-shaft F operates the various inclines of the cam-groove, serving to rock said shaft in an obvious manner.

The rock-shaft F is herein shown as carried by a tubular jacket f', bolted at f² to the web of the adjacent rail, said jacket having a laterally-flared portion f³ at the end thereof adjacent the switch, in which plays an arm f⁴ of the rock-shaft, loosely connected at f⁵ to a slide-bar f⁶, resting in a recess a², formed in the bed of the switch, said slide-bar being connected to the switch-point A² by a removable pin f⁷, so that any movement of the slide-bar f⁶ causes similar movement of the switch-point.

Adjacent the moving parts of the switch we provide an electric heater a³ in order to prevent any freezing and clogging thereof.

Referring again to Figs. 3 and 6, the car device for operating the switch is shown as comprising a rock-shaft g, provided at its forward end with a rock-arm g' and at its rear

end with a similar arm g², extending in the same direction, the latter arm having pivoted thereto at its outer end a trip g³, having one or more notches g⁴ in its outer edge to be engaged by a detent g⁵, secured to a casting g⁶, which incloses and guides the tappet g⁷ and contains a spring g⁸, bearing at its lower end against the end of the casting and at its upper end against a plate g⁹ on the trip, and thereby tending normally to hold said trip in raised position. The rock-shaft is operated by a plunger g⁹, resting loosely on the arm g', said plunger comprising a smooth shank g¹⁰ and flat head g¹¹, simply inserted in the floor h of the car. The object of this simple construction is to permit the driver or motorman to insert the plunger quickly at either end of the car, it being understood that similar car devices are provided at each end of the car, so that upon insertion of the plunger the car device is ready for operation and upon removal of the plunger the car device is rendered entirely inoperative, so that a passenger or meddler cannot interfere therewith.

The operation of our invention is as follows: The motorman having placed the plunger g⁹ at the forward end of the car, as shown in Fig. 3, will when he nears the switch observe whether the latter is properly placed in the direction in which his car should go, and if it is not he simply presses with his foot on the head g¹¹ of the plunger, and thereby depresses the trip-lever g³, the latter being locked in depressed position by the detent g⁵. As the car moves forward the lower end of the lever g³ enters the channel-block C and engages a projecting arm d³ of the wheel d⁴, thereby rotating the drum D the proper distance to rock the rock-shaft F, moving its arm f from an upper dwell d' to a lower dwell d², or vice versa. This movement communicates a similar movement to the arm f⁴ and, through the medium of the slide-block f⁶, shifts the switch-point from its previous position to an opposite position, so that if it was previously set for the main line it now becomes set for the siding, or vice versa. As the car moves forward the depending end of the trip-lever g³ is deflected by the bend c² in the channel-block, so as to disengage it from the detent g⁵ and permit the coiled spring g⁷ to restore it instantly to its raised position, and simultaneously therewith the incline c' raises it, so that it cannot by any possibility come in contact with the paving-stones and be damaged, and in case the spring g⁷ should become broken or should be omitted the incline alone will serve to restore the trip-lever to its original position. In fact, if desired, the bend c² may also be omitted, and the incline c' alone depended upon to restore the lever g³, as will be readily understood. As the wheel d⁴ is rotated by the trip-lever its inclined sides d' successively brush away all foreign matter which may have lodged in the channel-block, thereby automatically clearing the way them-

selvies without extraneous appliances, and, as before explained, if by any chance any foreign matter should get into the inclosure of the drum it would be effectually prevented 5 from inconveniencing the latter by reason of the several flanges, eaves, &c., before explained in detail. Furthermore, our invention is as readily operable in winter as in summer, for the reason that the heater devices, located as they are directly adjacent the moving parts, effectually prevent any freezing thereof.

By reason of the flat portions or dwells d' d'' the switch is positively locked in the positions 15 of extreme throw in either direction.

One point of considerable advantage in our invention resides in having the switch-point instantly detachable from the automatic operating mechanism described, this being accomplished 20 simply by taking out the removable pin f' . Under certain circumstances it is obvious that it is desirable to be able to shift the switch for a time without operating the ratchet-wheel, and our invention renders this 25 perfectly feasible for one movement only of the switch, if desired, or for many movements thereof, if required.

A main object had in view in our invention is to provide mechanism of extreme simplicity and such that the pavement need not be disturbed therefor to any greater extent than would be required for laying the usual track itself, and we have accomplished this by providing the simple mechanism shown and already 35 described, which is located compactly against the rail, the rock-shaft F being carried directly against the web of the rail, as stated, so that it occupies a space within and above the base of the rail, thereby requiring no more 40 space for its insertion than the rail itself requires.

It will be understood while we have herein shown a preferred embodiment of our invention we are not restricted thereto, but that 45 many changes in details of structure and arrangement and combination of parts may be resorted to without departing from the spirit and scope of our invention.

Having fully described our invention, what 50 we claim, and desire to secure by Letters Patent, is—

1. An automatic switch-operating device for street-railways, comprising a channel-block next to a rail of the track, an arm projecting horizontally across said channel-block, an inclined cam connected to and operated by said arm, a switch-point, a rock-shaft extending between and journaled adjacent said switch-point and said cam and having at its ends lateral arms, one in engagement with said cam and the other connected to said switch-point, whereby movement of said horizontal arm, and thereby of said cam, serves to rock said shaft axially and shift said switch, substantially as described.

2. An automatic switch-operating device

for street-railways, comprising a channel-block adjacent a rail of the track, an arm projecting across said channel-block, an inclined cam connected to and operated by said arm, a switch-point, a rock-shaft extending from said switch-point to said cam and having lateral arms, one in engagement with said cam and the other connected to said switch-point, whereby movement of said arm, and thereby of said cam, serves to rock said shaft and shift said switch, said cam having a dwell at the opposite ends of its incline, said dwell co-operating with the adjacent arm of the rock-shaft, to hold the same rigid and thereby lock the switch-point, substantially as described.

3. An automatic switch-operating device for street-railways, comprising a channel-block adjacent a track-trail, a vertical drum 85 carrying a wheel provided with arms extending horizontally across said channel-block, said arms having their forward sides sloping rearwardly relatively to the length of the channel in all positions of the arms therein, 90 whereby upon forward rotation of said wheel said rearwardly-sloping sides automatically remove foreign matter, a switch-point, and connections between said drum and said switch-point for operating the latter by movement of the former, substantially as described.

4. An automatic switch-operating device for street-railways, comprising a channel-block adjacent a track-rail, a vertical drum 100 having a cam-groove carrying a horizontal wheel provided with lateral arms extending horizontally across said channel-block, said arms having their forward sides beveled at an angle to slope rearwardly relatively to the 105 length of the channel in all positions therein, whereby upon forward rotation of said wheel said beveled sides automatically push foreign matter ahead along the channel, a switch-point, a rock-shaft extending between said 110 drum and said switch-point, said rock-shaft having an arm at one end in engagement with and actuated by said cam-groove, and an arm at its other end in connection with and to actuate said switch-point, substantially as described.

5. In a device of the class described, a rock-shaft, means to rock the same by the passage of a car, a switch-point, a slide connected to said rock-shaft and connected to said switch-point, and means for instantly connecting or disconnecting said slide from said switch-point, substantially as described.

6. In a device of the class described, a drum, operating means therefor, a switch-point, connections between said drum and switch-point for operating the latter from the former, and a housing for said drum, said drum having an outwardly projecting and depending flange, and said housing having an upwardly-projecting flange beneath and overhung by said drum-flange, for affording the latter free movement clear of all foreign matter, substantially as described.

7. In a device of the class described, a drum, operating means therefor, a switch-point, connections between said drum and switch-point for operating the latter from the former, and 5 a housing for said drum, said housing having at its upper end an annular flange adjacent said drum, said flange being provided with a rib, and said drum having an overhanging wheel provided with a recess to interlock with 10 said rib, substantially as described.
8. In a device of the class described, a drum, operating means therefor, a switch-point, connections between said drum and switch-point for operating the latter from the former, and 15 a housing for said drum, said housing having at its upper end an annular flange adjacent said drum, said flange being provided with a rib, and said drum having an overhanging wheel provided with a recess to interlock with 20 said rib, brackets beneath said annular flange, and an electric heater held in said bracket adjacent the wall of said housing, to maintain the latter and adjacent parts normally heated, as and for the purpose set forth.
- 25 9. In a device of the class described, a drum, operating means therefor, a switch-point, connections between said drum and switch-point for operating the latter from the former, and a housing for said drum, said housing having 30 at its upper end an annular flange adjacent said drum, said flange being provided with a rib, and said drum having an overhanging wheel provided with a recess to interlock with said rib, brackets beneath said annular flange, and an electric heater held in said bracket adjacent the wall of said housing, to maintain the latter and adjacent parts normally heated, recesses adjacent the switch-point, and an electric heater in said recess to 35 40 maintain the parts adjacent the moving switch-point in heated connection, as and for the purpose set forth.
10. In a device of the class described, a switch-point, a rock-shaft to operate the same, 45 means to actuate said rock-shaft, and a tube inclosing said rock-shaft, said tube being se-

cured adjacent the web of a track-rail, between and within the outer edges of the base and head of the rail, said tube having at its end adjacent the switch a laterally-flared funnel-shaped portion, substantially as described. 50

11. A switch-point, an actuating-cam therefor, connections between said cam and said switch-point, an arm carried by said cam, a channel-block adjacent a track-rail, said arm projecting across said channel-block, the channel of the latter extending parallel to the rail for the main part of its length, and having at its forward end a lateral bend away 60 from the rail, combined with a car device comprising a depending arm, and means to raise and lower said arm, the latter when in its lowered position being adapted to travel in said channel and thereby actuate the arm 65 carried by said cam, said car device being provided with a spring normally tending to raise said arm, and a detent arranged to engage and hold said arm depressed, said bent-away part of said channel disengaging said 70 arm from said detent and permitting the spring to restore the arm to its raised position, substantially as described.

12. The herein-described car device, comprising a rock-shaft, arms extending therefrom at its opposite ends, a plunger engaging one of said arms and adapted to be depressed by the foot, a depending arm connected to the free end of the second arm of said rock-shaft, a spring normally holding 80 said depending arm in raised position, and a detent adapted to engage and hold said depending arm in depressed position, substantially as described.

In testimony whereof we have signed our 85 names to this specification in the presence of two subscribing witnesses.
